CLAIM

The ornamental design of the bowler terminal with CRT (console), as shown and described.

DESCRIPTION

FIG. 1 is a perspective view of a bowler terminal with CRT (console) in accordance with the invention;

FIG. 2 is a front-elevational view of the bowler terminal with CRT (console) shown in FIG. 1;

FIG. 3 is a side-elevational view of the bowler terminal with CRT (console) shown in FIGS. 1 and 2 and which is a mirror image of the opposite side;

FIG. 4 is a top or plan view of the bowler terminal with CRT (console) shown in FIGS. 1-3;

FIG. 5 is a side-elevational view illustrating the back of the bowler terminal with CRT (console) shown in FIGS. 1-4; and,

FIG. 6 is a bottom plan view of the bowler terminal with CRT (console) as shown in FIGS. 1-5.
